UNITED STATES PATENT OFFICE.

WILLIAM M. SUHR, OF NEW YORK, N. Y.

BOILER-COVERING COMPOSITION.

SPECIFICATION forming part of Letters Patent No. 339,820, dated April 13, 1886.

Application filed February 19, 1886. Serial No. 192,532. (No specimens.)

To all whom it may concern:

Be it known that I, WILLIAM M. SUHR, of the city, county, and State of New York, have invented a new and Improved Boiler-Covering 5 Composition, of which the following is a specification, reference being had to the accompanying drawings, in which—

Figure 1 is a cross-section of a boiler or tube covering made of my composition, and Fig. 2 is a longitudinal section of the same.

My composition consists of the following ingredients, combined in the proportions stated, viz: solution of alum and soda, one part; mixture of hair or felt, one thirty-second part; 15 asbestos fiber, one thirty-second part; mineral wool, one thirty-second part; cork and sawdust, two-thirds part; plaster-of-paris or other substance in sufficient quantity to form a mortar. These ingredients are to be thoroughly 20 mingled by agitation to form a mortar.

The above-named composition is either cast in suitable molds in sections or otherwise, or is put on the boiler or tube to be covered by the use of a trowel and held in place by sheets 25 of canvas, paper, or felt, or by means of sta-

ples, straps, wires, or any other suitable fastening.

This composition forms a reliable fire-proof and at the same time a non-conducting boiler and tube covering.

The covering A, as shown in the drawings, is made in two parts, B and C, of the above-described composition, which parts B and C are fastened together by staples D, and surrounded by a sheet of canvas, paper, felt, or 35 other suitable material, E.

Having thus fully described my invention, I claim as new and desire to secure by Letters Patent—

The herein-described composition of matter 40 to be used as a boiler or pipe covering, consisting of a solution of alum and soda, a mixture of hair or felt, asbestos fibers, mineral wool, cork and sawdust, and plaster-of-paris or other similar substance, in the proportions 45 specified.

WILLIAM M. SUHR.
